UNITED STATES PATENT OFFICE

138,866

DESIGN FOR A PROPELLER

Coy Orsett, Boston, Mass.

Application May 6, 1944, Serial No. 113,521

Term of patent 14 years

(Cl. D71—1)

To all whom it may concern:

Be it known that I, Coy Orsett, a subject of the King of Great Britain, residing at 121 Beacon Street, Boston, in the county of Suffolk and State of Massachusetts, have invented a new, original, and ornamental Design for a Propeller, of which the following is a specification, reference being had to the accompanying drawing, forming part thereof.

The present application is a continuation-in-

part of application, serial Number D-109,452, filed Feb. 4, 1943.

Figure 1 is a front elevational view of a propeller showing my new design; and

Figure 2 is a side elevational view thereof.

I claim:

The ornamental design for a propeller, as shown.

COY ORSETT.
